United States Patent

Des. 237,100
Patented Oct. 7, 1975

237,100

FINGER RING

Bernard I. Mechanic, 2425 Oakton St.,
Evanston, Ill. 60202

Filed Feb. 5, 1973, Ser. No. 329,584

Term of patent 3½ years

Int. Cl. D11—01

U.S. Cl. D45—10 C

FIG. 1

FIG. 2

FIG. 3

FIG. 1 is a top plan view of a finger ring showing my new design;

FIG. 2 is a right side elevational view thereof—left side view is identical; and

FIG. 3 is a front elevational view thereof—rear elevational view is identical.

I claim:

The ornamental design for a finger ring, as shown and described.
